TREAD FOR FOOTWEAR

Jose Paredes Castano, Elche, Alicante, Spain, assignor to Jose Paredes, S.L., Elche, Alicante, Spain

Filed Dec. 18, 1974, Ser. No. 533,892

Term of patent 14 years

Int. Cl. D2—04

U.S. Cl. D2—320

FIG. 1 is a bottom plan view of a tread for footwear showing my new design;

FIG. 2 is a cross-sectional view taken along line 2—2 of FIG. 1.

I claim:

The ornamental design for a tread for footwear, substantially as shown and described.
